LISTING CALCULATOR

Loring Pickering Crosman, South Orange, N. J.,
assignor to Monroe Calculating Machine Company, Orange, N. J., a corporation of Delaware

Application August 7, 1942, Serial No. 454,025

3 Claims. (Cl. 197—127)

The invention relates to listing calculators and other machines provided with a shiftable carriage having a rotatable platen, an object of the invention being to provide the machine with certain improvements upon the combined paper hold back and line finder device of my co-pending application for Patent Serial Number 373,676, filed January 8, 1941, patented June 8, 1943, No. 2,321,014. Another object is to provide the machine with an improved front-feed paper guide having pressure rolls engaging the platen to feed a paper sheet thereover in rotation of the platen. Other objects and advantages will appear hereinafter.

The invention consists in the novel construction and combinations of parts as hereinafter set forth in the claims.

In the accompanying drawings,

Figure 1 is a section of the invention as applied upon the line 1—1, Figure 2.

Figure 2 is a front elevation of the invention as applied, with parts removed and parts broken away.

Figure 3 is a right side elevation of the machine showing the invention as applied, parts being broken away.

Figure 4 is a left side elevation of the same.

Figure 5 is a detail top plan of the carriage, with parts broken away.

Figure 6 is a section on the line 6—6, Figure 5 on an enlarged scale, parts being broken away.

Figure 7 is a detail perspective view of one of the paper edge guides.

Figure 8 is a detail perspective view of the depending plate of said guide.

Figure 9 is a detail perspective view of the right hand carrier member for the wire line finder.

The invention is shown as applied to a Monroe listing calculator, such for instance as disclosed in my Patent No. 1,946,572, dated February 13, 1934, modified in accord with the disclosure of my co-pending application for Patent Serial Number 421,803, filed December 5, 1941, patented June 29, 1943, No. 2,323,205.

In the drawings, the numeral 1 designates a shiftable carriage having mounted thereon a rotatable platen 2, provided with means to be described for rotating the same and yieldably retaining the platen in position as rotated.

A front-feed paper guide includes a plurality of separate spring-metal plates 3, each of which at the lower end thereof is rigidly secured to a transverse shaft 5 having rotary bearings in the carriage end frame and at the upper end there-

of is provided with a pressure roll 4 engaging the platen to feed a paper sheet thereover in rotation of the platen. Means are provided for adjusting said shaft 5 rotatably in its carriage end frame bearings and for holding the adjustment to vary the pressure of the said rolls 4 upon the platen including identical U-form clamps 6 upon said shaft having bolts 6' upon loosening which said adjustment may be accomplished, whereupon the bolts are tightened to hold the adjustment.

A combined paper hold back and line finder wire 7 extends the full length of the platen and has normal raised position to hold back the paper sheet, manipulable means to be now described being provided as disclosed in my aforesaid co-pending application for Patent Serial Number 373,676 with certain structural modifications, for locking said front-feed paper guide in normal position; for disabling said locking means and conjointly displacing said paper guide to open position with its pressure rolls spaced from the platen and said wire downwardly for line finding purposes; for locking said paper guide in open position and said wire against return to normal position, and for disabling the last named locking means, conjointly restoring the parts to normal position and rendering again effective the first named locking means.

Inasmuch as the paper hold back and line finder wire and the front-feed paper guide both extend the full length of the platen, the manipulable means referred to embodies parts provided in duplicate at the platen ends, which parts will be described in the singular in some cases.

The right and left duplicate levers 8 have mounted thereon through bolts 9 thereof right and left carrier members 10 for said paper hold back and line finder wire 7. This wire is continuous and flexible and is made fast at one end thereof to one of said carrier members by insertion of the knotted end of the wire within a diametric notch of stud 11 of said member; thence extending the full length of the platen to provide one wire stretch, around a pulley 12 of the other carrier member to form a bend in the wire; thence extending reversely the full length of the platen to provide a second wire stretch parallel to and spaced from the first wire stretch, around a pulley 13 of the first named carrier member to form another bend in the wire; the wire thence extending rearwardly around a stud 12' of the first named carrier member at which point it is provided with a tension adjusting spring 14. The right and left carrier members

10 are provided each with parallel slots 9' engaged by the aforesaid bolts 9 of the right and left levers 8, thereby providing for adjustment of said carrier members upon said bolts and of the paper hold back and line finder wire 7 relative to the platen for proper positioning of said wire.

Mounted upon the bolts 9 of the levers 8 is also an upper paper guide 15, extending the full length of the platen and having end flanges 16 perforations of which are engaged by said bolts, whereby manipulation of said upper paper guide will displace both of said levers 8, both carrier members 10 and the paper hold back and line finder wire 7 therewith. The upper paper guide 15 is spaced rearwardly from the paper hold back and line finder wire 7 by an interval 8', admitting of passage of the paper sheet 8" forwardly of said upper paper guide, through said interval and rearwardly of said wire 7 between the same and the platen 2, thereby providing for full visibility of the upper portion of the paper sheet on and above the printing line.

Right and left right-angle edge guides 17 for the paper sheet are mounted upon the upper paper guide 15 and are adjustable therealong slidably. The body of each of said edge guides has a hooked forward end 18 fitting over the forward edge portion of said upper paper guide, and rear end slots 19 engaged by angularly bent lugs 20 of the upper end of a depending plate 21, said lugs resting upon the top surface of the edge guide body and coiled springs 22 connecting the lower end of said depending plate with said forward hooked end 18 to yieldably hold the edge guide down to the paper guide.

The front-feed paper guide 3 is locked in normal position by a toggle joint, the upper member 10' of which is pivoted at its upper portion at 11' to the platen carriage frame and the lower member 12" of which has pivotal connection 13' with the tail arm 14' of U-form clamp 6 (considered as a lever), coiled spring 15' connecting joint member 12" and an extension of clamp 6 and being normally tensioned to hold joint member 10' in stop engagement with transverse brace rod 10" connecting the carriage end frames and the joint members aligned to prevent the bowing thereof in one direction, said bowing serving to further tension said spring 15' and to displace said front-feed paper guide to open position with its pressure rolls spaced from the platen as will be explained.

Each lever 8 is fulcrumed at 17' to a sector 18' loosely mounted upon the platen shaft 2' and held in normal position by a coiled spring 19' tending to rotate the sector clockwise (Fig. 6), and stop lug 20" with which a projection 20' of the sector contacts. The lower arm of each lever 8 has its upper edge concentric with the platen shaft and of greater radius than that of and spaced from the arcuate edge of the related sector by an arcuate space 23' within and at one end of which said stop lug 20" is normally located. Thus the lower arm of normally positioned lever 8 has stop engagement with said lug 20" against pivotal movement of the lever in one direction and the upper arm of said lever has stop engagement with the hub 18" of said sector against pivotal movement of the lever in the opposite direction, with some margin to allow for different thicknesses of one or more paper sheets 8" with or without carbon sheets. Thus also upon forward manipulation of the upper paper guide 15, the right and left duplicate levers 8 will be moved bodily as a unit with sectors 18'

upon the platen shaft as a center against the tension of springs 19' to bring the paper hold back and line finder wire 7 downwardly to the printing line, which is the point A of the dot and dash line of Fig. 6, but only temporarily as will be explained. The lug 20" is a lateral lug of a member 24' of a second toggle joint pivoted at 25' to the platen carriage frame, the other member 26' of said joint being pivoted at 27' to the upper member 10' of the first named toggle joint.

The above stated forward manipulation of the upper paper guide 15 moves the right and left duplicate levers 8 and the sectors 18' as a unit therewith a distance substantially measured by the length of the arcuate space 23', this unitary movement being stopped by contact of the forward walls of the radial arcuate notches 29' (concentric with fulcrums 17'), of said sectors with the lugs 20", at which time the respective fulcrums 17' of the levers 8 will become aligned with the respective pivots 25' of the members 24' of said second toggle joints, and pivotal movement of the levers 8 upon their fulcrums then taking place as a consequence of continued forward manipulation of the upper paper guide 15, the following will take place:

The paper hold back and line finder wire 7 will be brought farther downwardly to the point B of the dot and dash line of Fig. 6, in an arcuate path away from the platen and the printing line from fulcrum 17' as a center and the lugs 20" will be moved within the notches 29' of the sectors against the inner ends of the notches as a stop, thereby actuating joint members 24' to bow 35 the first named toggle joints and disable the lock thereof for holding the front-feed paper guide in normal position; displacing said front-feed paper guide to open position wherein its pressure rolls will be spaced from the platen and aligning the members of each of said second toggle joints to lock the front-feed paper guide in open position and to lock the sectors 18' as moved to prevent the return of the levers 8 and of the paper hold back and line finder wire 7 to normal position.

In aligning the members of each of said second toggle joints, the outer arms 30' of the members 26' of said joints (considered as levers), which outer arms are at their outer ends rigidly connected by cross rod 31', will be brought to and set in position for movement in unison upon manipulation of said cross rod.

The parts being in the positions above stated, and a paper sheet or sheets 8" with or without carbon sheets being inserted in the machine forwardly of the upper paper guide 15 and of the platen, through the interval 8', rearwardly of the paper hold back and line finder wire 7 now spaced from the platen, and rearwardly of the front-feed paper guide and its pressure rolls also now spaced from the platen, to approximately correct position and pressed by the operator with the thumbs of both hands rearwardly against the upper paper guide 15, will cause reverse movement of the duplicate levers 8 upon their fulcrums and bring the paper hold back and line finder wire 7 back to the point A of the dot and dash line of Fig. 6 into close proximity to the platen at the correct height to show or find the printing line upon the paper sheet. At this point the free ends of the rear arms of the duplicate levers 8, which ends are slightly hooked as shown, will contact one side and a corner of the duplicate stops 32', which stops are the squared heads of 70 the pivots 11' of the upper members of the toggle

joints first named, thereby resisting the pressure of the operator's thumbs so that the paper sheet and the paper hold back and line finder wire 7 will be properly held.

The paper sheet is now adjusted with reference to the paper hold back and line finder wire 7 nicely to the printing line and while holding the paper in this position against the upper paper guide 15 by his thumbs the operator will with certain of the fingers of both hands push forwardly upon the cross rod 31' which is within convenient reach and has been previously adjusted to and set in position for manipulation as stated. This will bow said second toggle joints and disable the lock thereof for holding the front-feed paper guide in open position, whereupon the tensioned springs 19' will restore the parts to normal position, with exception of the levers 8, which are still manually held in engagement with said stops as stated and sectors 18' upon which said levers are mounted and which are similarly held.

The paper sheet being thus properly adjusted to the printing line and so held by the normally positioned pressure rolls of the front-feed paper guide, the operator naturally releases his thumb pressure upon the paper sheet and the upper paper guide 15, whereupon the tensioned springs 19' will restore the sectors 18' and the levers 8 with the paper hold back and line finder wire 7 as a unit to normal position, wherein as aforesaid said wire is raised to form a hold back for the paper sheet.

The upper paper guide 15 may be provided with a tear-off or knife edge for use with a paper tape.

The parallel stretches of the paper hold back and line finder wire 7 are spaced apart similarly to the printed lines on the paper sheet, for use in aligning to print on the same line in ordinary work and to print on the next line below in ledger and statement work upon a single operation of said manipulable means for displacing said wire downwardly for line finding purposes.

The points C and D (Fig. 6), have the same significance with respect to the lower stretch of the combined paper hold back and line finder wire 7 as have the points A and B of said figure with respect to the upper stretch of said wire.

Upper and lower spaced rails 23 of the carriage have opposite upper and lower tracks 24 and each opposite lateral tracks 25, upper and lower stationary spaced channel bars 26 of the stationary main frame having opposite upper and lower tracks and each opposite lateral tracks spaced from those of said rails. Upper and lower anti-friction means are located between said tracks.

The upper and lower rails 23 fit at their ends within notches 31 of the carriage end frames and a flattened tubular brace 32 has bolt connection with said rails to connect and hold the rails securely in place within said notches. Tie rods 32' connect the end frames of the carriage 1 and hold the latter securely against brace 32 to form a rigid unit.

The upper and lower stationary spaced channel bars 26 extend at both end portions thereof beyond the stationary machine frame for better support of a long carriage and have a connecting member 28' rigidly secured thereto by bolts 37 to form a unit therewith, said connecting member being stiffened by having the sheet metal of which it is composed centrally channeled and provided with upper and lower forwardly bent flanges 33', thereby providing seats 33 within

which seats fit projections 34 of the machine frame ends. Other projections 35 of the machine frame ends fit within perforation seats of said connecting member. The upper and lower spaced channel bars include each a rectangular cover plate 36, detachably bolted to the forwardly bent flanges 33' at 37. The bearing between the upper and lower channel bars of the stationary main frame and the upper and lower rails of the carriage is claimed in the divisional application for patent, Serial Number 495,324, filed July 19, 1943.

Upper and lower adjustable hooks 39 have bolt connection 40 with the stationary machine frame, arcuate slots 42 of said hooks being engaged by said bolts which work therein. These upper and lower hooks are engaged with registering perforations or eyes of the cover plates 36 and the forwardly bent flanges 33'. The detachable connection between the main frame and the unit comprising the upper and lower channel bars and their connecting member is claimed in the divisional application No. 524,756, filed March 2, 1944.

A line spacing pawl 41 is pivoted at 43 to one arm of a bell crank 44, the latter being fast to rock shaft 45 having bearings in the carriage end frames, a bell crank 46 being fast to the opposite end of said shaft, these bell cranks having forward extending arms 47 connected at their forward ends by a cross bar 48 so that movement is transmitted from one bell crank to the other and both bell cranks and said cross bar work as a unit. A spring 49 connected to the tail arm of bell crank 46 normally tensions said unit downwardly against a stop 53 to be described, whereby said cross bar is normally positioned at the upper end of a passage 50 located between the tubular brace 32 and the connecting member 28' of the channel bar unit. The line spacing pawl is maintained in normal position by means of a spring device 51, tending to yieldably maintain a fixed distance between a stud 42' of said pawl and a stud 44' of bell crank 44, with which studs said spring device has connection at its ends, whereby the line spacing pawl may be actuated by the usual roller arm of the machine into engagement with the ratchet wheel 52 against tension of said spring device and will be restored to normal position by said spring device upon release of said roller arm. The line spacing pawl being rocked by said roller arm in an arc about shaft 45 as a center into engagement with said ratchet wheel, the pawl will ride over one or more teeth of said ratchet wheel during the forward stroke of the machine in accord with the setting of a lever 53. During the return stroke of the machine, the bell cranks 44 and 46 and the cross bar 48 are rocked as a unit reversely, thus line spacing the platen. The lever 53 is adjustable to engage its tooth 53' with either of three notches 54 of an arm 55 pivoted at 56 and urged downwardly by spring 57 to maintain the tooth and notch engagement, the bell crank 46 being tensioned downwardly by its spring to engage either of two steps 46' thereof with said tooth of the lever 53 constituting the aforesaid stop. Thus the stroke of the two bell cranks 44 and 46 and the cross bar 48 working as a unit may be varied to vary the line spacing.

At the extreme end of the return stroke of the machine said bell cranks and cross bar working as a unit will be given a short movement to release the line spacing pawl from the ratchet wheel, whereupon said spring device 51 will act to retract the bell cranks 44 and 46 and said cross bar as

a unit as well as the line spacing pawl to normal position so that the platen may be rotated by the use of the twirler knob. The usual spring-urged detent 58 has a roller 59 engaging the ratchet wheel to yieldably maintain the platen in adjusted position.

Means are provided for stopping the shiftable carriage in predetermined columnar positions in tabulating operations upon successive manipulation of a tabulating lever 60 and shifting of the carriage including a continuous series of tabulating stops 61 loosely mounted upon a shaft 62, which stops are contiguous, manipulable means being provided for slightly rotating the stops 61 upon said shaft for setting purposes including a setting lever 63, all as fully disclosed in my aforesaid co-pending application for patent Serial Number 421,803.

I claim:

1. In a machine of the class described, having a rotatable platen, a front feed paper guide having pressure rolls engaging the platen to feed a paper sheet thereover in rotation of the platen, a combined paper hold back and line finder wire device extending the full length of the platen having normal raised position to hold back the paper sheet, and manipulable means for displacing said device downwardly for line finding purposes and for restoring the same to normal position; said paper hold back and line finder wire device including two parallel wire stretches spaced apart similarly to the printed lines on the paper sheet for use in aligning to print on the same line in ordinary work and to print on the next line below in ledger and statement work upon a single operation of said means for displacing said device downwardly for line finding purposes.

2. In a machine of the class described, having a rotatable platen, a front feed paper guide having pressure rolls engaging the platen to feed a paper sheet thereover in rotation of the platen, a combined paper hold back and line finder device extending the full length of the platen having normal raised position to hold back the paper sheet, and manipulable means for displacing said

device downwardly for line finding purposes and for restoring the same to normal position; said manipulable means including right and left spaced levers and said paper hold back and line finder device including right and left spaced carrier members and two parallel wire stretches mounted upon said carrier members and spaced apart similarly to the printed lines on the paper sheet for use in aligning to print on the same line in ordinary work and to print on the line next below in ledger and statement work upon a single operation of said manipulable means for displacing said device downwardly for line finding purposes, said carrier members having adjustable means of connection with said levers for proper positioning of said wire stretches.

3. In a machine of the class described having a rotatable platen, a front-feed paper guide having pressure rolls engaging the platen to feed a paper sheet thereover in rotation of the platen, a combined paper hold back and line finder device extending the full length of the platen having normal raised position to hold back the paper sheet, and manipulable means for displacing said device downwardly for line finding purposes and for restoring the same to normal position; said manipulable means including right and left spaced levers and said paper hold back and line finder device including end pulleys, right and left spaced carrier members therefor, and a continuous flexible wire having bends around said end pulleys and two parallel stretches spaced apart similarly to the printed lines on the paper sheet for use in aligning to print on the same line in ordinary work and to print on the line next below in ledger and statement work upon a single operation of said manipulable means for displacing said device downwardly for line finding purposes, said carrier members having adjustable means of connection with said levers for proper positioning of said wire stretches, said wire being secured at one end thereof to one of said end pulleys and at its other end being provided with a tensioning spring connection with the platen carriage frame.

LORING PICKERING CROSMAN.
